DESIGN FOR A CARD FOLLOWER

Thomas A. Hearn, Ludlow, Ky., assignor to The Globe-Wernicke Company, Norwood, Ohio, a corporation of Ohio

Application September 11, 1942, Serial No. 108,181

Term of patent 14 years

To all whom it may concern:

Be it known that I, Thomas A. Hearn, a citizen of the United States and a resident of Ludlow, in the county of Kenton and State of Kentucky, have invented a new, original, and ornamental Design for a Card Follower, of which the following is a specification, reference being had to the accompanying drawing, forming a part hereof.

In the drawing:

I claim:

The ornamental design for a card follower, as shown.

THOMAS A. HEARN.
